UNITED STATES PATENT OFFICE.

AXEL H. ENGSTRÖM, OF PHILADELPHIA, PENNSYLVANIA, ASSIGNOR OF
ONE-HALF TO GEORGE S. GANDY, OF SAME PLACE.

APPARATUS FOR REGENERATING EXHAUST-STEAM.

SPECIFICATION forming part of Letters Patent No. 556,964, dated March 24, 1896.

Application filed November 27, 1895. Serial No. 570,297. (No model.)

To all whom it may concern:

Be it known that I, AXEL H. ENGSTRÖM, a subject of the King of Sweden and Norway, but now residing at the city of Philadelphia, in the county of Philadelphia and State of Pennsylvania, have invented certain new and useful Improvements in Apparatus for Regenerating Exhaust-Steam, of which the following is a specification.

My invention has relation to apparatus for revivifying or regenerating exhaust or low-pressure steam of the type wherein the exhaust or low-pressure steam is first heated by live steam, mixed and compressed by said live steam, whereby the heat units of the exhaust or low-pressure steam are preserved and utilized and said exhaust or low-pressure steam is increased both in pressure and temperature for use again in the cylinders of the engine, and in such connection it relates particularly to the construction and arrangement of such an apparatus.

The principal objects of my invention are, first, to provide a regenerator of simple construction adapted to receive both live and exhaust or low-pressure steam, and to first heat the exhaust or low-pressure steam by means of the live or high-pressure steam, then compress the heated exhaust by means of the hot steam and simultaneously mix with the heated and compressed exhaust or low-pressure steam the live steam; second, to provide a regenerator consisting of a casing divided into three chambers, the exhaust-steam entering the external and internal chambers and surrounding the intermediate chamber into which live steam is admitted, whereby the exhaust-steam is heated by said live steam, the exhaust-steam being drawn out of its chambers by the live steam and escaping in compressed form from the contracted outlets of the chambers, the outlet of the intermediate live-steam chamber being contracted and formed adjacent to the outlets of the two exhaust-steam chambers; third, to provide in such regenerator a valve controlling the outlet of the live-steam chamber; and, fourth, to provide a regenerating apparatus consisting of a series of regenerators connected together, each of which is adapted, when required, to be cut out or cut into the series, whereby the

efficiency of the apparatus may be readily and quickly decreased or increased.

My invention consists of an apparatus for revivifying or regenerating exhaust or low-pressure steam, constructed and arranged substantially as hereinafter described and claimed; and my invention further consists of the regenerator constructed and arranged substantially as hereinafter described and claimed.

The nature and scope of my invention will be more fully understood from the following description, taken in connection with the accompanying drawings, forming part hereof, and in which—

Figure 1 is a longitudinal central section of the regenerator embodying the main features of my invention. Fig. 2 is a cross-section taken on the line *x* *x* of Fig. 1. Fig. 3 is a similar section taken on the line *y* *y* of Fig. 1. Fig. 4 is a diagrammatic view, partly sectioned, showing the connections between the exhaust, the primary and secondary boilers, and a series of regenerators, and illustrating the method of cutting out or in one or more of said regenerators; and Fig. 5 is a similar view, enlarged, illustrating in detail the method of connecting up the regenerators.

Referring to the drawings, A represents the regenerator, consisting of a casing or shell *a*, having an inlet *a*¹ for exhaust-steam, an inlet *a*² for live steam, and an outlet *a*³ for the revivified exhaust-steam. Within the casing *a*, and preferably below the inlet *a*¹ of the exhaust, is placed a tubular nozzle *b*, connected with the live-steam inlet *a*², and having an expanding outlet *b*¹. Within this tubular nozzle *b*, and having a range of movement through a stuffing-box *b*², at one end thereof, is a tubular or hollow stem *d*, carried by the spindle *d*¹, threaded in the end of the casing *a*, and passing through a stuffing-box *c*³ thereof. This spindle *d*¹ and the hollow stem *d* may be advanced or retracted in the nozzle *b*, by means of the hand-wheel *d*², as illustrated in detail in Fig. 1. A portion of the stem *d* extends outside of and to the right of the tubular nozzle *b*, into the chamber *e*, formed in the casing or shell *a*, and the interior of said stem *d* is in communication with said chamber *e*, through the opening or

openings e^3 in said stem. The nozzle b , stem d , and casing a divide the chamber e into three concentric compartments, of which the external and internal contain exhaust while the intermediate contains live steam. The casing a , at about the point where the expanded outlet b' of the nozzle b terminates, is contracted into an abrupt shoulder f , and then tapered gradually, as at f' , and finally slightly 5 enlarged into a bulbous form, as at f'' , just before the contracted outlet a^3 . There is thus formed within the casing a three chambers, the chamber e , in which the exhaust first enters, the chamber e' of tapering form, and the 10 chamber e^2 of bulbous or enlarged form. The outlet g from the chamber e into the chamber e' is contracted by reason of the formation of the abrupt shoulder f at that point and of the exterior taper b^3 of the nozzle-outlet b' . The 15 nozzle-outlet b' is of expanding annular form by reason of the formation of an external shoulder d^4 at the outlet of the stem d and the internally-tapered wall of the outlet b' of the nozzle. A contracted expanding outlet 20 d^5 is formed on the stem d by means of the internal taper at the end of the stem d and the tapered reducing-piece h held in the casing by means of the ribs h' . By screwing the 25 hollow stem d and spindle d' toward or away from this tapered reducing piece h the size of the outlet d^5 is decreased or increased, thus 30 regulating the amount of exhaust-steam escaping through the stem d into the chamber e' , and this movement of the stem d and spindle d' correspondingly decreases and increases 35 the outlet b' of the nozzle b as the shoulder d^4 of the stem d approaches or recedes from the internal tapered wall of the outlet b' .

The exhaust-steam enters the chamber e 40 and a portion is discharged through the outlet g into the chamber e' , while the remainder passes through the hollow stem d , entering the same through the openings d^3 . While the exhaust-steam is in the chamber e and hollow 45 stem d it is heated by the live steam in the nozzle b , forming an intermediate compartment of the chamber e , the stem d or internal compartment being blanketed by the live steam in the nozzle b , and the external compartment of the chamber e being heated by 50 radiation from the exterior of the nozzle b .

The live steam, as it escapes through the outlet b' into the chamber e' , sucks the exhaust out of the stem d and chamber e through 55 the contracted opening or outlet g . The exhaust and live steam are mixed in the chamber e' and from thence forced into the expanding-chamber e^2 , at which point the live steam will compress the exhaust. During the 60 compression of the exhaust a certain portion thereof will condense, and the latent heat given off during this condensation is absorbed by the exhaust-steam, whereby the temperature of the exhaust is considerably increased. 65 The steam on leaving the outlet a^3 of the regenerator will be under required pressure and will be raised to required temperature.

In Figs. 4 and 5 I have indicated diagrammatically a complete plant in which several of the regenerators are coupled up, so that 70 they may act either successively or singly upon the exhaust-steam. Referring to said figures, B represents a primary boiler containing or generating live or high-pressure steam. C represents a secondary boiler in 75 which the revivified exhaust is accumulated for use in the engine cylinder or cylinders D . The boiler B and boiler C are connected by a pipe B' , in which is placed an automatic regulator-valve B^2 , adapted to maintain a constant 80 and uniform difference in pressure between the two boilers. From the boiler B leads a pipe B^3 having suitable connections or branches B^4 , each controlled by a valve B^5 leading to the inlets a^2 of the regenerators A . 85 The exhaust from the engine-cylinders D is conducted by the pipe D' to a separator and accumulator or reservoir D^2 , at the top of which is placed a relief-valve D^3 , adapted to open when the exhaust accumulates too rapidly and to permit the discharge of a portion of the exhaust to the open air. From the separator and accumulator D^2 a pipe D^4 is led, supplying each regenerator with exhaust-steam by means of branch pipes D^5 , each of which 95 leads to an inlet a' of a regenerator A . The outlet a^3 of each regenerator A leads into a steam-separator E and the revivified exhaust, after the water of condensation is separated thereby, is led by a pipe D^6 to the main exhaust-supply D^4 . 100

Each branch pipe D^5 and each pipe D^6 is provided with a regulating and cut-off valve F and F' , respectively, and the main exhaust-supply pipe D^4 is also provided with similar 105 valves D^2 , one of said valves being located between the branch pipe D^5 and pipe D^6 , as indicated in the drawings. The pipe D^4 discharges into the secondary boiler C .

From the above-described arrangement it 110 will be seen that the exhaust-steam from the cylinders D is led by pipes D' and D^4 and branch pipes D^5 into a succession of regenerators A , in which it is heated, compressed, and mixed with live steam. The exhaust, 115 after it leaves the first regenerator, is further treated in the next succeeding regenerator until finally the exhaust is raised to required temperature and pressure and passes into the boiler B . 120

If for any reason one or more of the regenerators A refuse to operate, or the number of regenerators required is to be decreased, any one of said regenerators may be cut out by shutting off the exhaust entering the particular inlet a' from a branch pipe D^5 by shutting off the live steam entering the inlet a^2 from the pipe B^4 and by shutting off communication from the outlet a^3 of said regenerator with the pipe D^4 . Thus, for instance, if the middle regenerator of the three illustrated in Fig. 4 is to be cut out the valve F of its branch pipe D^5 is turned to close the supply 125 of exhaust to said regenerator, the valve B^5 130

of the pipe B⁴ is turned to shut off the supply of live steam to said regenerator, and the valve F⁵ in the pipe D⁶ is turned to shut off communication of pipe D⁴ with the separator 5 E. The supply of exhaust-steam to the successive regenerator A is regulated by the series of valves F² in the pipe D⁴.

Having thus described the nature and objects of my invention, what I claim as new, 10 and desire to secure by Letters Patent, is—

1. A regenerator for revivifying exhaust or low-pressure steam consisting of a casing, the interior of which is provided with a chamber divided into three concentric compartments, 15 an inlet for exhaust-steam into the external and internal compartments and an inlet for live steam into the intermediate compartment, said exhaust-compartments being provided with contracted outlets and said live-steam compartment being provided with an 20 expanding outlet adjacent to the outlets of the exhaust-compartment, substantially as and for the purposes described.

2. A regenerator consisting of a casing provided with an inlet for exhaust-steam, an inlet for live steam and an outlet for mixed exhaust and live steam, a tubular nozzle arranged in said casing connected with the live-steam inlet and provided with an expanding 25 outlet, a hollow stem placed within the nozzle in communication with the interior of the casing, a reducing-piece held in the casing and forming at the end of the tubular stem a contracted expanding outlet, said hollow stem 30 and space in the casing surrounding the tubular live-steam nozzle being in communication with the exhaust-steam inlet, all arranged so that the exhaust-steam chambers thus formed lie respectively around the exterior and within 35 the interior of said live-steam nozzle, a spindle carrying said stem and means for advancing and retracting said stem and spindle in the casing toward or away from said reducing-piece, substantially as and for the purposes described.

3. A regenerator comprising a casing divided into three chambers in communication with each other, each provided with a contracted outlet, the first of said chambers being divided into three concentric compartments in the external and internal of which exhaust-steam is led, while in the intermediate compartment live steam is led to heat the exhaust 45 in the other compartments, the second chamber being of tapered and contracted form, the exhaust and live steam from the first chamber escaping therein through the contracted and expanded outlets and being mixed together in 50 said second chamber, and the third chamber being of bulbous or enlarged form to constitute at its contracted outlet a compression-chamber for the mixed steam, substantially 55 as and for the purposes described.

60 4. A regenerator consisting of a casing pro-

vided with an inlet for exhaust-steam, an inlet for live steam and an outlet for mixed exhaust and live steam, a tubular nozzle arranged in said casing connected with the live-steam inlet and provided with an expanding 65 outlet, a hollow stem placed within the nozzle in communication with the interior of the casing, a reducing-piece held in the casing and forming at the end of the tubular stem a contracted expanding outlet, said hollow stem 70 and space in the casing surrounding the tubular live-steam nozzle being in communication with the exhaust-steam inlet, all arranged so that the exhaust-steam chambers thus formed lie respectively around the exterior and within 75 the interior of said live-steam nozzle, a spindle carrying said stem and means for advancing and retracting said stem and spindle in the casing toward or away from said reducing-piece, substantially as and for the purposes described.

5. In a system of regenerating exhaust-steam from the cylinders of engines, a primary boiler containing high-pressure steam, a secondary boiler adapted to receive the revivified 85 exhaust and to supply the same to the engines for reutilization, a series of regenerators having inlets in communication with the exhaust from said cylinders and inlets for live steam from the primary boiler, said regenerators 90 adapted to increase said exhaust in pressure and temperature and to mix the exhaust with the live steam, the outlet of each regenerator being connected with the exhaust-inlet of the nextsucceeding regenerator, substantially as 95 and for the purposes described.

6. The combination of the series of regenerators having live-steam and exhaust-steam inlets, a primary boiler containing live steam, a pipe leading therefrom and branched to 100 connect with the live-steam inlet of each regenerator, a pipe conveying exhaust from engines or other steam apparatus and branched to connect with the exhaust-inlet of each regenerator, a pipe leading from the outlet of 105 the first regenerator to the exhaust-inlet of the next regenerator in the series, a secondary boiler connected with the outlet of the last regenerator in series and adapted to supply the engines with revivified exhaust-steam, 110 and valves adapted to shut off the exhaust and live steam entering each regenerator, substantially as and for the purposes described.

In testimony whereof I have hereunto set my signature in the presence of two subscribing witnesses.
